UNITED STATES PATENT OFFICE.

JACOB WOLSTEN, OF NEWARK, NEW JERSEY.

DESIGN FOR A COMBINED SPOON AND FORK.

53,171.

Specification for Design.

Patented Apr. 1, 1919.

Application filed August 24, 1918. Serial No. 251,327. Term of patent 14 years.

To all whom it may concern:

Be it known that I, JACOB WOLSTEN, a citizen of the United States, residing in Newark, in the county of Essex and State of New Jersey, have invented a new, original, and ornamental Design for a Combined Spoon and Fork, of which the following is a specification, reference being had to the accompanying drawing, forming part thereof.

The figure is a plan view of a combined spoon and fork, showing my new design.

The handle shown in the accompanying drawing forms no part of my design which is applicable to any handle of suitable size, shape or form.

I claim:

The ornamental design for a combined spoon and fork as shown.

Signed at New York, in the county of New York and State of New York, this 22 day of August, 1918.

JACOB WOLSTEN.
